DESIGN FOR A TELEPHONE CASING

Thomas McCann, Brooklyn, N. Y.

Application May 29, 1936, Serial No. 62,897

Term of patent 14 years

To all whom it may concern:

Be it known that I, Thomas McCann, a citizen of the United States, residing at 1344 East 35th St., Brooklyn, city and State of New York, have invented a new, original, and ornamental Design for a Telephone Casing, of which the following is a specification, reference being had to the accompanying drawing, forming part thereof.

The figure is a perspective view of a telephone casing showing my new design, the four sides not shown being substantially plain.

I claim:

The ornamental design for a telephone casing, as shown and described.

THOMAS McCANN.
